RECORD AND METHOD OF MAKING THE SAME

Samuel E. Adair, Chicago, Ill., assignor, by mesne assignments, to Bendix Radio Corporation, Baltimore, Md., a corporation of Delaware

Application November 20, 1937, Serial No. 175,646

5 Claims. (Cl. 179—100.1)

This invention relates to records and to method of making the same and more particularly to records for controlling and sensory systems.

The invention is illustrated as adapted to systems in which a record for the reproduction of a sensory effect carries thereon a blocking component to regulate the operation of a device or series of devices.

One object of the invention is to provide a record for a controlling and sensory system in which there is little possibility of confusion between the sensory and blocking components.

Another object of the invention is to provide a record for a controlling and sensory system in which the device blocking component is adapted to cause actuation of controlled devices in response to its temporary interruption.

Other objects advantages and novel features of the invention will become apparent from the following description of the illustrative embodiment shown in the accompanying drawing, in which;

Figure 1 is an enlarged diagrammatic representation of the operating frequency component of the record;

Figure 2 is an enlarged diagrammatic representation of the sensory component;

Figure 3 is an enlarged diagrammatic representation of the resultant sensory track;

Figure 4 is a diagrammatic representation of one method of producing the record; and Figure 5 is a diagrammatic representation of a system in which the record is employed.

The invention is illustrated as embodying a disc record 10 having recorded thereon some sound or other sensory effect which it is desired to reproduce and a blocking component 12 superimposed thereon.

As shown in Fig. 3 the record 10 consists of a single recorded track incorporating both a normal sound recording 14 (Fig. 2) which shall be called the sound track, and a device-operating recording 12 (Fig. 1), which shall be called the blocking component; that is to say the normal sound track 14 is combined with the blocking component 12, so that record 10 consists mainly of recorded vibrations 13 (Fig. 3) comprising the resultant of the sound track 14 and the blocking component 12.

According to the present invention, the blocking component consists of a low frequency sound oscillation present at every portion of the sound track except at that portion in which it is desired to operate or start to operate a device or series of devices.

It can readily be seen that there is very little possibility of the normal sound track having an oscillation of exactly the same frequency and in exactly the same phase relationship as that of the blocking component at the portion of the sound track in which the blocking component is absent. This insures that the device to be operated will be operated only at the proper time.

The record 10, may be prepared in any suitable manner. One desirable method being illustrated in Fig. 4 and including a suitable recorder 100, a device such as microphone 102 for delivering to the recorder through an amplifier 103 the normal sound vibrations such as the speech, music or other sound it is desired to reproduce, and a device for delivering to the recorder the blocking frequency. The device for delivering the blocking frequency is shown as an oscillator 104 and leads 106 having a normally closed switch 108. The leads 106 connect the oscillator to the recorder so that the recorder can deliver to the record the blocking component as long as the switch 108 remains closed. This switch may be opened at the time during the recording of the normal sound track at which it is desired to operate the device 32.

The recorder 100 cuts the sound track on the record 10 as the record on turntable 110 is turned preferably at substantially constant speed by motor 112 through suitable gear means 114.

It is to be understood that the record 10 may be of any suitable type known in the art, that is, it may be a groove formed in a cylinder or disc, as shown, a photographic record on a film, or a magnetic record on wire.

The system (Fig. 5) in which the record is to be employed is generally similar to that described and claimed in Patent No. 2,116,314, granted May 3, 1938, and the copending application of John E. Jenkins and Samuel E. Adair, Ser. No. 200,652, filed April 7, 1938.

An electrical pickup 16 may be employed to convert the mechanical vibrations on the record to electrical oscillations which may be amplified by an amplifier 18 and reproduced through a loudspeaker 20. A filter 22 may, if desired, be employed in this circuit to filter out the operating component so that it will not be reproduced by the loudspeaker.

A device operating circuit, in parallel with the above circuit may consist of a filter 24 connected to the pickup 16. The filter 24 is so designed as to permit only those oscillations to pass which correspond in frequency to that of the device operating component.

The filter 24 may be connected to an amplifier 28 which in turn delivers the amplified operating current to the relay 30. Whether the amplifier 28 is necessary or not depends upon the sensitivity of the relay.

The filter 24 need not be employed if the relay 30 is of the tuned type.

The relay 30 is shown normally biased by spring 31 in switch closed position, but the blocking component being present at all times to energize relay 30 except when it is desired to close the relay switch, the switch is held open until that particular time at which the blocking component is absent on the record.

15 The absence of the device operating component actuates the relay. This closes circuit 32 which may be employed to operate a device or series of devices.

20 While only one illustrative embodiment has been shown and described it is not intended that the scope of the invention be limited to the form shown nor otherwise than by the terms of the appended claims.

What is claimed is:

25 1. In a controlling and sensory system, a record comprising a composite sensory component and blocking component, said blocking component comprising a predetermined frequency added to said sensory component and being interrupted at spaced intervals, and means included in said system for inaugurating a control function upon interruption of said blocking component.

30 2. In a controlling and sensory system, a rec-

ord comprising a composite sensory component and blocking component, said blocking component comprising a predetermined frequency added to said sensory component and being interrupted at spaced intervals, and control means 5 in said system normally restrained from operation during the reproduction of said blocking component.

3. In a controlling and sensory system, a record 10 containing a sensory component, a blocking component contained on such record, said blocking component being interrupted at spaced intervals, and means included in said system for inaugurating a control function upon interruption of said blocking component.

4. In a controlling and sensory system, a record 15 containing a sensory component, a blocking component on said record comprising a frequency less than 150 cycles per second, said blocking component being interrupted at spaced intervals, and means included in said system for inaugurating a control function upon interruption of said blocking component.

5. In a controlling and sensory system, a record 20 containing a sensory component, a blocking component contained on said record, said blocking component being interrupted at spaced intervals, means for reproducing said sensory component and said blocking component, means for segregating said reproduced components, and 25 means responsive to said segregated blocking component for restraining the inception of a control function.
